(57) **CLAIM**

The ornamental design for a throw-away tip for cutting tool, as shown and described.

DESCRIPTION

FIG. 1 is a front view of an embodiment of a throw-away tip for cutting tool showing my new design;
FIG. 2 is a rear view thereof;
FIG. 3 is a top view thereof;
FIG. 4 is a bottom view thereof;
FIG. 5 is a right side view thereof;
FIG. 6 is a left side view thereof;
FIG. 7 is a first perspective view thereof;
FIG. 8 is a second perspective view thereof;
FIG. 9 is a third perspective view thereof;
FIG. 10 is a side view seen in the direction of arrow X of FIG. 1;
FIG. 11 is a cross sectional view taken along line XI-XI of FIG. 1;
FIG. 12 is an enlarged view of XII-XII portion of FIG. 3;
FIG. 13 is an enlarged view of XIII-XIII portion of FIG. 4;
FIG. 14 is a first referential view showing the state in which a workpiece is machined with the throw-away tip for cutting tool according to the embodiment attached to a holder; and,

(Continued)

FIG. 15 is a second referential view showing the state in which a workpiece is machined with the throw-away tip for cutting tool according to the embodiment attached to a holder.

The portions indicated by the solid line are portions for which a design registration as a partial design is sought. The broken lines in the drawings depict unclaimed environmental subject matter. The long dashed and short dashed lines shown in the drawings indicate only a boundary between the claimed portion and the unclaimed portion.
